John F. Leslie
BY
George J. Ottsch
ATTORNEY

UNITED STATES PATENT OFFICE.

JOHN F. LESLIE, OF MISHAWAKA, INDIANA.

FABRIC-ROLL-END PROTECTOR.

Application filed September 17, 1923. Serial No. 663,042.

To all whom it may concern:

Be it known that I, JOHN F. LESLIE, a citizen of the United States, residing at Mishawaka, in the county of St. Joseph and

5 State of Indiana, have invented certain new and useful Improvements in Fabric-Roll-End Protectors, of which the following is a specification.

The invention relates to roll protectors of 10 the type wherein dished members are placed within the open end of the roll for protecting the edges thereof and for forming a compartment in which material used in connection with the roll may be stored, and has 15 for its object to provide a wire extending through the chamber of the roll and provided with portions outside the caps for the reception of a twisting tool, whereby the caps may be securely tied together.

20 A further object is to provide the ends of the wire with transversely disposed U-shaped members having their outer arms longer than their inner arms and extending through elongated apertures in the caps and 25 adapted to receive a twisting tool whereby the ends of the wire may be twisted around the long arms of the U-shaped members for tying the caps together and holding the same in position. The elongated apertures allow 30 the U-shaped members to be worked through the caps.

A further object is to form the wires sufficiently long whereby a portion thereof may wrap around the long arms of the U-shaped 35 members during a twisting operation.

With the above and other objects in view the invention resides in the combination and arrangement of parts as hereinafter set forth, shown in the drawing, described and 40 claimed, it being understood that changes in the precise embodiment of the invention may be made within the scope of what is claimed without departing from the spirit of the invention.

45 In the drawing:—

Figure 1 is a vertical longitudinal sectional view through a fabric roll, showing the device applied thereto.

Figure 2 is a longitudinal sectional view 50 through one of the caps showing one end of the wire extending therethrough and ready to receive the twisting tool.

Figure 3 is a view in elevation of one of 55 the caps, showing the end of the wire twisted, for holding the cap in position.

Figure 4 is a plan view of one of the U-

shaped members carried by one end of the wire and showing a twisting tool thereon.

Figure 5 is a view similar to Figure 4, but showing one of the U-shaped members 60 partially twisted.

Figure 6 is a view in side elevation of one of the U-shaped members, showing the same with a twisting tool applied thereto and after being twisted.

Referring to the drawing, the numeral 1 designates a roll of material, for instance of roofing material, and 2 the chamber thereof which extends entirely through the roll. In present practice the necessary material, such as nails, is placed in the compartment 2, so that when the roll reaches the consignee all of the necessary material for applying the roofing is within the chamber 2. It has been found that rolls of this 75 character become damaged, and to obviate this difficulty the dished caps 3 are provided, which caps have cylindrical portions 4 extending into the ends of the chamber 2 and annular flanges 5 which engage the ends 80 of the roll for protecting the same, which caps are at present used and tied together. The tying devices for tying caps together as at present constructed are complicated and are either formed from heavy material or 85 constructed in a manner whereby the variations and distance between the caps will not be taken care of in a manner whereby the caps will be positively held in close engagement with the ends of the roll. The 90 tying device comprises a wire 6 which extends preferably axially through the chamber 2 and has its end provided with transversely disposed U-shaped members 7 formed by bending the ends of the wire. 95

The outer arms 8 of the U-shaped members 7 are longer than the inner arms 9 thereof, therefore it will be seen that when the twisting tool 10 is applied to the U-shaped members 7 as shown in Figure 4 and the twisting tool rotated the long arms 8 of the U-shaped members 7 will be moved into engagement with the ends of the wires 6 and the continued rotation of the twisting tool 10 will twist the ends of the wires 6 around the long arms 8, consequently the wires 6 may be drawn taut with the twisted ends thereof in close engagement with the outer faces of the caps 3 as shown in Figure 1, thereby securely holding said caps in the 110 ends of the chamber 2 and in close engagement with the ends of the roll 1. The ends

of the wires 6 extend through elongated slots 11 in the caps 3, which elongated slots allow the caps 3 to be worked into position by the movement of the cap or by the movement of the U-shaped members 7 for working the U-shaped members through the apertures 11. If so desired one of the U-shaped members 7 may be twisted before assembling, and a single end twisted after the caps 10 and wire have been assembled. By having elongated arms 8, it is obvious that during the twisting operation the U-shaped members will not be reduced in length so that they would pull through the apertures 11 15 as would be the case if the loop were longitudinally disposed in relation to the wires 6.

From the above it will be seen that a tying device is provided for end caps of fabric roll protectors, which tying device 20 is provided with transversely disposed U-shaped loops at the ends of a wire extending through the roll, which loops may receive a twisting tool whereby the U-shaped loops may be rolled or twisted onto the ends of 25 the wire and into close and binding engagement with the caps, thereby positively holding the caps in position and in close engagement with the ends of the roll. It will also be seen that the caps may be easily and 30 quickly removed by applying a twisting tool to the twisted portions of the wire and untwisting the same, or by cutting off the ends of the wire with a cutting tool.

The invention having been set forth what 35 is claimed as new and useful is:—

1. The combination with a roll of material having a chamber extending therethrough, caps engaging the ends of said roll, of a member extending through said 40 chamber and through the caps, the ends of said member being provided with transversely disposed U-shaped portions twisted upon the ends of the member and into engagement with the outer faces of the caps.

45 2. The combination with a roll of material having a chamber extending therethrough, caps carried by the ends of the roll, of a wire extending through said caps and chamber, the ends of said wire being 50 provided with transversely disposed U-shaped portions, the outer arms of said U-shaped portions being longer than their inner arms whereby when the U-shaped portions are twisted, the ends of the wire will be 55 twisted around the long arms of the U-shaped portions.

60 3. The combination with a roll of material having a chamber extending therethrough, caps carried by the ends of the roll, of a wire extending through elongated apertures of said caps and through the chamber, the ends of said wire being provided with transversely disposed U-shaped portions having their outer arms longer than their 65 inner arms, whereby upon a twisting of the

U-shaped portions the ends of the wire will be twisted around the long arms of the U-shaped portions.

4. The combination with a roll of material having a chamber extending therethrough, caps carried by the ends of the roll, of a wire extending through an elongated aperture of one of the caps and anchored to the other cap, the end of said wire which extends through the elongated 70 aperture of one of the caps being provided with a transversely disposed U-shaped portion adapted to be twisted onto the end of the wire and into engagement with the adjacent cap.

5. The combination with a roll of material having a chamber extending therethrough, caps carried by the ends of the roll, a wire extending through an enlarged aperture of one of the caps and anchored to 85 the other cap, the end of said wire being provided with a transversely disposed U-shaped portion adapted to be twisted in a transverse position onto the end of the wire and into engagement with the adjacent caps. 90

6. The combination with a roll of material having a chamber extending therethrough, caps carried by the ends of the roll, a wire extending through an enlarged aperture of one of the caps and anchored 95 to the other cap, said wire having its end provided with a transversely disposed U-shaped portion, the outer arm of said U-shaped portion being longer than the inner arm, said U-shaped portion being adapted to 100 be twisted in a transverse position onto the end of the wire with the end of the wire twisted around the long arm thereof.

7. The combination with a roll of material having a chamber extending therethrough, caps engaging the ends of said roll, of a member extending through said chamber and connected to one of the caps, the other end of said member extending through the other cap and provided with a 105 transversely disposed U-shaped portion twisted upon the end of the member and into engagement with the outer face of the adjacent cap.

8. The combination with a roll of material having a chamber extending therethrough, caps carried by the ends of the roll, of a wire extending through said chamber, one end of said wire being anchored to one of the caps, the other end of the wire extending through the outer cap, said last named end of the wire being provided with a transversely disposed U-shaped portion, the outer arm of said U-shaped portion being longer than its inner arm, whereby 110 when the U-shaped portion is twisted the end of the wire will be twisted around the long arm of the U-shaped portion. 115

In testimony whereof I affix my signature.
JOHN F. LESLIE.
